UNITED STATES PATENT OFFICE.

ILDEPHONSE QUINET AND ARTHUR DENIS, OF DENAIN, FRANCE.

APPARATUS EMPLOYED IN SINKING PITS OR SHAFTS.

SPECIFICATION forming part of Letters Patent No. 284,895, dated September 11, 1883.

Application filed March 19, 1883. (No model.) Patented in France October 20, 1882, No. 151,630.

To all whom it may concern:

Be it known that we, ILDEPHONSE QUINET and ARTHUR DENIS, both citizens of the Republic of France, residing at Denain, in France, 5 have invented a new and useful Improvement in Apparatus to be Employed in Sinking Pits or Shafts, (for which we have obtained a patent in France bearing date October 20, 1882, No. 151,630,) of which the following is a specification.

At the present time in working mines the deepening of the hoisting-shafts is effected with the aid of cages and corves as follows: At the bottom of one of these cages is suspended, by 15 means of a rope, a tub with a movable bottom and of a capacity of about, say, ten bushels, which receives the earth that is broken down in the sinking when the miners have fired their "shots." The cage is caused to descend 20 upon the stops of the lowest stage, and the tub is then lowered to the bottom, where the operatives fill the same. The whole is then raised again, the operatives close a trap-door, and bring a corf held in readiness in a drift or gallery. The whole apparatus is lowered again, so 25 as to allow the tub to be emptied into the corf, which is then withdrawn into the drift, and the cage again descends to the bottom to allow a new charge to be filled in, and so on till all the rubbish is removed. When the emptying is done, 30 the tub is detached from the cage, is placed in a drift, and the corves are replaced in the cage to be sent to the pit's mouth, so that in conveying the material broken down for sinking about a yard by about five yards diameter in 35 twenty-four hours the tub has to travel upward seventy-five times from the bottom to the receiving-stage, where two workmen are employed, and then the cages with the corves 40 have to ascend thirty-five times from that stage to the bank, whereby considerable loss of time is entailed for the miners occupied in the sinking. By working in this manner it will be necessary to finish the sinking before the drifts 45 are begun at the intermediary stages and before the commercial working can commence, as the engine is not always sufficient for raising the rubbish and for lowering the materials. Twenty-four workmen will, according to 50 the nature of the strata to be traversed, sink

on an average about two feet by five yards diameter in twenty-four hours. They would thus require about ninety days for sinking, say, one hundred and sixty to one hundred and seventy feet, and as much for preparing 55 the side drifts for about six hundred and twenty feet toward the south, and also the north, using mechanical boring devices therefor. When some thirty to forty feet are sunk, the pit is built in ascending and placing guide-posts, say, at each yard. The materials have to be lowered with corves to the last stage and pass into the galleries or drifts, and are afterward lowered by means of the tub to the point where the sinking has stopped. It will be obvious that this produces loss of time and slowness of progress. To obviate this great loss of time and to accelerate the work is the object of the following invention, which allows the bottom of the pit to be continually reached 65 with two cages. This system consists of two movable frames, A, Figures 1 and 2, which are both vertical sections of portions of the shaft, which are always applied to the last guides fixed in the pit. These frames are suspended 70 each by two ropes, B, of a certain length, and this may vary from, say, sixty-five to one hundred feet between the lower roller, C, and the top one, D, round which the ropes pass. They carry at the other end a counter-weight, E, of 75 sufficient weight to cause the frames to reascend and to keep it against the guides.

When the rubbish is to be removed, the engine is started, one of the cages arrives upon one of the frames, carries it away by its weight, 85 and occupies the position shown in dotted lines in Fig. 1, which indicate that part of the sinking where no guides are yet provided. When passing upon the frame-work, the cage sets a signal-bell off, so as to warn the operatives of its arrival. These then fill the corves and give the signal, and the cage is raised, and the frame drawn up by the counter-weight takes its position underneath the fixed guides, so as to afford a continuous guidance for the raising of 90 the cage to the pit's mouth. The second cage in turn passes into the second frame and carries it to the bottom, so that reloading may take place, and these operations are repeated 95 till the loose material is entirely removed. 100

When from, say, thirty to forty-five feet have been sunk, the material required for masonry and for the permanent guides in the pit is lowered. The beams for the guides are put in 5 gradually as the masonry proceeds, and the guides are only begun when the bottom of the course is reached. A length of about ten yards of the shaft is left with guides unconstructed, so that it may not be exposed to the effects of 10 the shots while sinking.

The advantages offered by this method are the following: First, we dispense with four men per twenty-four hours for receiving the 15 tub at the last stage; second, we dispense with the tub and with the rope on which it is suspended, this latter having always to be equal in length to the depth of the shaft to be sunk; third, less loss of time by the workmen employed for boring and constructing the shafts, 20 consequently a greater progress per twenty-four hours and diminution of the cost; fourth, preparation of the drifts and galleries at the same time that the shaft is being sunk, consequently the mine can be worked immediately 25 after the shaft is sunk, and consequently, also, another loss of time is avoided, to the advan-

tages of the owner, who is enabled to dispose of his produce during a time at least equal to that required for sinking; fifth, it is possible to set up, when a new shaft is being sunk, all the 30 building machinery and material required for the working, so that as soon as the level of the first heading is passed the machines can be directly brought into operation, just as if the shaft were in full working.

35

We claim—

1. In appliances for sinking shafts, a fixed guide or way combined with a suspended movable frame carrying a cage or receptacle for the material to be raised or lowered, said frame 40 and receptacle being arranged to descend below the lower end of the way, substantially as and for the purposes specified.

2. The combination, with the movable guides A A, of the ropes B B and counterbalance- 45 weights E E, substantially as and for the purposes set forth and shown.

ILDEPHONSE QUINET.
ARTHUR DENIS.
